DESIGN FOR A GLOVE.

No. 38,191.

Specification for Design.

Patented Aug. 21, 1906.

Application filed May 17, 1906. Serial No. 317,397. Term of patent 14 years.

To all whom it may concern:

Be it known that I, FRANK L. EASTERLY, a citizen of the United States, residing at Gloversville, in the county of Fulton and State of New York, have invented a new, original, and ornamental Design for Gloves, of which the following is a specification, reference being had to the accompanying drawing, forming part thereof.

The single figure of the drawing is a view in perspective of the back of a glove, showing my new design.

I claim—

The ornamental design for a glove, as shown.

FRANK L. EASTERLY.
